UNITED STATES PATENT OFFICE

JOHN G. FEHN, OF DES MOINES, IOWA

DESIGN FOR A BASE FOR A LAUNDRY APPLIANCE

Application filed May 31, 1930. Serial No. 35,872. Term of patent 14 years.

To all whom it may concern:

Be it known that I, JOHN G. FEHN, a citizen of the United States, and a resident of Des Moines, in the county of Polk and State of Iowa, have invented a certain new, original, and ornamental Design for a Base for a Laundry Appliance, of which the following is a specification, reference being had to the accompanying drawing, forming part thereof.

Figure 1 is a perspective view of a base for a laundry appliance showing my new design.

Figure 2 is a plan view of the same.

I claim:

The ornamental design for a base for a laundry appliance, as shown.

JOHN G. FEHN.
